CINCINNATI COFFIN COMPANY, OF CINCINNATI, OHIO, A CORPORATION OF
OHIO.

CASKET-HANDLE.

1,344,855.

Specification of Letters Patent. Patented June 29, 1920.

Application filed November 6, 1919. Serial No. 336,049.

To all whom it may concern:

Be it known that we, ALBERT R. BETTS and PAUL J. GOKE, citizens of the United States of America, and residents of Cincinnati, in the county of Hamilton and State of Ohio, have invented a new and useful Improvement in Casket-Handles, of which the following is a specification.

In casket handles it is desirable for appearance sake to conceal the hinge that connects the handle to its lug plate. But the means by which this has heretofore been attained, have been weak and inconvenient to construct.

It is the object of our invention to provide a casket handle with concealed joints that is strong and easy to manufacture.

This object is attained by the means described in the specification and illustrated in the accompanying drawings, in which:

Figure 1, is a front view of a casket handle embodying our invention.

Fig. 2, is a rear view of the same.

Fig. 3, is a sectional view taken upon line 25 3—3 of Fig. 2.

The casket handle embodying our invention comprises a metal plate A, having near its lower end a central aperture which is

formed by striking inward two lugs, a, a', in which are formed aligned apertures, which 30 are adapted to receive a journal pin B whose ends b, b' pass through perforations in the lugs e, e' of the handle E.

The journal pin has a central loop or offset, the sides of which may be compressed to 35 facilitate the passage of the ends b, b' through the perforations in the lugs e, e', b, b'.

The lug plate A has perforated bosses a², a³, to receive screws by means of which 40 the lug plate is attached to the casket.

Having thus described our invention, what we claim is:

In a handle of the class described the combination of a lug-plate having an aperture, 45 inwardly projecting perforated lugs at the ends of the aperture, a handle having at one end perforated lugs adjacent to the lugs of the lug-plate, and a wire having straight ends and a central off-set adapted to be compressed to facilitate insertion of its ends through the perforations. 50

In testimony whereof, we have subscribed our names this 4th day of November, 1919.

ALBERT R. BETTS.

PAUL J. GOKE.
